CHANNEL SECTION PARTICULARLY FOR USE IN
THE CONSTRUCTION OF LOAD-CARRYING
FRAMEWORKS

Warren R. Attwood, 4077 2nd St., Wayne, Mich.

Filed Sept. 25, 1961, Ser. No. 66,851

Term of patent 14 years

(Cl. D13—1)

FIG. 1 is a perspective view of a channel section showing my new design, the side and end not shown being like the respective side and end shown.

FIG. 2 is a cross-sectional view of the channel section of FIG. 1 showing the symmetrical nature thereof.

The characteristic features of my design reside in the longitudinal recesses on opposite sides of the channel section and the flanges bordering such recesses.

I claim:

The ornamental design for a channel section particularly for use in the construction of load-carrying frameworks, as shown and described.
